MOLD BOX FOR BUTTER AND THE LIKE

Filed Aug. 20, 1924

Patented Sept. 27, 1927.

1,643,508

UNITED STATES PATENT OFFICE.

CHARLES F. MILLER, OF CEDAR RAPIDS, IOWA.

MOLD BOX FOR BUTTER AND THE LIKE.

Application filed August 20, 1924. Serial No. 733,089.

My invention relates to mold-boxes for use with butter and like materials, to form the same into blocks or slabs for storage and refrigeration, and preparatory to cutting the 5 blocks into prints of standard sizes. It is the object of my invention to provide a mold-box for the purposes stated, of simple, strong and durable construction, and in which a uniform depth of the mold is maintained regardless of expansion and contraction 10 of the sides of the box, due to absorption of moisture and drying of the moisture therefrom. The mold-box provided by my invention is particularly adapted for use in forming blocks or slabs of hard butter or 15 the like, which are to be cut into print-sizes by the methods and means described in my Patent No. 1,414,994, issued May 2, 1922; and my mold-boxes may also be advantageously employed for producing blocks of 20 butter, oleomargarine, or other materials, where it is desirable that the blocks be of uniform size, and when the characteristics of the molded material are such that the 25 mold-surfaces must be of wood.

In the accompanying drawings Fig. 1 is a perspective view of a mold-box embodying my invention, Fig. 2 is a plan view of the same, Fig. 3 is a longitudinal vertical section 30 thereof, Fig. 4 is a transverse section on the line 4—4 of Fig. 3, the sides of the mold being shown partly dried or shrunken, and Fig. 5 is a partial transverse section, similar to Fig. 4, but showing the sides expanded.

In the construction of mold-boxes for butter, it is preferable that the mold-surfaces be of wood, the primary reason for such preference being that the butter will not cling or adhere to a wood surface when the latter is moist; it being understood, of course, that the natural wood surface should be employed, without coating of paint, varnish or other protective material which would prevent the absorption of water by 40 the wood. Wood is also preferable by reason of its lighter weight, cheapness, facility of working, and the fact that it will not become corroded by chemical reaction with the salt, water or other butter-constituents, 45 and will not contaminate the butter by imparting thereto any unnatural taste or flavor.

In mold-boxes for forming butter into blocks or slabs which are subsequently to be cut to print-sizes, it is also desirable that 50 the blocks or slabs be of uniform size, very

slightly larger than a multiple of the print-sizes, so that by a slight trimming of one or more sides of the block or slab the dimensions thereof may be reduced to an exact multiple of the print-sizes. With an 60 ordinary mold-box made of wood, the amount of expansion due to absorption of moisture by the wood is such that the blocks of butter molded therein will be greatly oversized, and thus require excessive trimming, if the mold is proportioned to form a block of the correct size when the wood is 65 in a normal, dry or shrunken condition. It is well-known that the swelling or expansion of wood by absorption of water is almost wholly lateral to the grain of the wood, the variation in longitudinal dimensions being so small as to be inappreciable, and these characteristics of wood are utilized in my improved mold-box, to produce a mold of 70 which the capacity will be substantially unaltered by wetting or drying thereof.

Referring now to the structure shown in the drawings, the mold-box is rectangular in form and has fixedly connected side-portions comprising a pair of longitudinal members 10 and a pair of transverse members 11, the ends of said transverse members fitting into vertical grooves at the inner or adjacent sides of the members 10 near the 80 ends thereof. Adjoining the upper edges of the transverse members, at the outer sides thereof, the cross-pieces or cleats 12 are secured thereto by screws 13, said cross-pieces 85 constituting means which may be conveniently grasped for lifting the box. Screws 14 are extended through the sides of the longitudinal members 10 into the ends of the transverse members 11. The members 10 are also connected to each other by clamp-bolts 15 and 16, which extend across the 90 ends of the box adjoining the outer sides of the transverse members 11, the upper clamp-bolts 15 passing through grooves 17 at the inner sides of the cross-pieces 12, as 95 best shown in Fig. 3. The side-portions or members 10 and 11 are also secured to each other by the metal angle-plates 18, one of which is provided at each corner, each angle-plate having arms which extend from the 100 corner along the lower edges of the respective members and are secured thereto by screws (not shown). The angle-plates, besides serving to securely connect the side-members of the box, constitute shoes which 105 110

prevent wear and splintering of the lower edges of the wood members. In the lower edges of the longitudinal members 10, at transversely alined positions equidistant from the ends, are formed the rectangular notches 19, the longitudinal arms of the angle-plates 18 extending across the open lower ends of said notches, as shown. From the upper edges of said notches 19, openings extend up vertically through the members 10 to the upper edges thereof, and through said openings are extended the bolts 20 which support the metal channel-bars 21. Said channel-bars extend transversely between the notches 19 at opposite sides of the box, the ends of the bars fitting loosely within the notches and being secured to the bolts 20 by nuts 22 screwed upon the threaded lower ends thereof. The heads of the bolts are preferably thin and spherio-segmental in form, so as to project but slightly above the upper edges of the members 10, and adjoining the heads are squared portions which are driven into the upper ends of the openings and prevent rotation of the bodies, while the main cylindrical body-portions of the bolts fit somewhat loosely in the openings. The flanges of the channel-bars 21 extend downwardly, so that their flat upper sides form wide supporting surfaces for the bottom-member 24 of the mold. Said bottom-member is proportioned to fit loosely within the fixed rectangular frame formed by the members 10 and 11, and is provided on its lower side with one or more transverse cleats 25 which are suitably secured thereto, as by screws 23, to prevent warping of said bottom-member.

It will be understood that in the members 10 and 11, which constitute the fixed frame or side-portions of the mold, the grain of the wood extends longitudinally of the pieces, so that any expansion or contraction of said members, due to absorption of moisture or drying thereof, will not appreciably alter the length or width of the mold. The lateral expansion or shrinkage of said members 10 and 11 will considerably alter the over-all depth of the box, but will not affect the inside depth of the mold, because of the fact that the loose bottom-member is supported upon the cross-bars 21 which are suspended by the bolts 20 from the upper edges of the box, and the length of said bolts is not varied except by microscopic elongation or contraction due to thermal changes. Expansion or shrinkage of the wood sides of the mold will, therefore, merely vary the position of the cross-bars 21 with relation to the lower edges of the side-members, and the bottom-member 24 will

be maintained in a substantially fixed relation to the upper edges of the mold, as will be clearly apparent by a comparison of Figs. 4 and 5, the latter showing the sides expanded, and the former showing the same partly dried or shrunken in lateral dimensions.

My improved mold-box is employed in the usual manner, being filled with the butter while the same is comparatively soft and plastic, then being placed under refrigeration until the butter is hard, or frozen if storage is to be continued for a considerable time. When the molded blocks or slabs are to be cut to print sizes, the mold-boxes are inverted upon a table, the blocks ejected therefrom by pushing upon the loose bottom-members while the side-portions are lifted away, and the bottom-members then stripped from the upper sides of the blocks or slabs, thus leaving the latter resting free upon the table, ready for passage through the cutting mechanism.

The nuts 22 at the lower ends of the bolts 20 may be employed to secure an exact adjustment of depth of the mold, and after such adjustment is made it need not be changed unless it is desired to change the depth of the molded blocks.

The metal parts of the mold-box should, of course, be such as not to suffer corrosion, and this result is preferably attained by employing therein Monel metal or other non-corrosible metal, such as the so-called "stainless steel" alloys which are now becoming commercially available. The use of such materials is preferable to coating or plating of the surfaces of corrosible metal parts, since the protective coatings may be broken through or worn away after a short period of use, thus exposing the original material and allowing corrosion thereof to occur.

Now, having described my invention, what I claim and desire to secure by Letters Patent is:

A mold-box for butter and the like, comprising a rectangular box-frame of wood wherein the grain extends longitudinally of the frame-members, the lower edges of said frame having transversely alined notches therein, metal shoes affixed to said lower edges and extending across said notches, cross-bars having the ends thereof extending loosely into said notches and movable vertically relative thereto, suspension-members secured to said cross-bars and extending to the upper edge of the frame to support the cross-bars therefrom, and a bottom-member supported upon said cross-bars.

CHARLES F. MILLER.
